TIRE

James G. Balmer, Jr., Birmingham, Norbert T. Kuypers,
Detroit, and Robert G. Smith, Birmingham, Mich., as-
signors to United States Rubber Company, New York,
N.Y., a corporation of New Jersey

Application April 26, 1956, Serial No. 41,219

Term of patent 14 years

(Cl. D90—20)

Fig. 1

Fig. 2

Fig. 3

Fig. 4

Fig. 1 is a side elevational view of a tire showing our new design,

Fig. 2 is an enlarged sectional and fragmentary perspective view of the sidewall of the tire shown in Fig. 1,

Fig. 3 is a detail sectional view taken substantially on the plane indicated by line III—III of Fig. 1; and

Fig. 4 is a perspective fragmentary sectional view of Fig. 1.

The characteristic features of our design reside in a tire having a sidewall provided with a circumferentially-extending rib, said rib being provided with circumferentially-extending and spaced recesses in the outer face thereof of a color different from that of the rib, the sur-

face portions of the rib between said recesses imparting a spoke-like effect, substantially as shown in full lines on the drawings.

We claim:

The ornamental design for a tire, substantially as shown and described.
